(57) CLAIM

The ornamental design for a disposable diaper for pets as shown and described.

DESCRIPTION

1.1 : Perspective

1.2 : Front

1.3 : Back view, showing an uncut tail aperture

1.4 : Top

1.5 : Bottom

1.6 : Left

1.7 : Right

1.8 : Back view, showing a torn tail aperture

1.9 : Perspective view, showing a first condition of use

1.10 : Perspective view, showing a second condition of use

This article is a disposable diaper for pets. An uncut tail aperture is shown in 1.3; the diaper is altered by tearing the tail aperture as shown in 1.8, 1.9 and 1.10. The broken lines depict portions of the disposable diaper that form no part of the claimed design. The dash-dot-dash broken lines define boundaries of the claim and form no part thereof.
